US00D796514S

(12) **United States Design Patent** (10) **Patent No.:** **US D796,514 S**
Xu (45) **Date of Patent:** **** Sep. 5, 2017**

(54) **ADAPTER**

(71) Applicant: **FOXCONN INTERCONNECT TECHNOLOGY LIMITED**, Grand Cayman, KY (US)

(72) Inventor: **Yin-Chao Xu**, Kunshan (CN)

(73) Assignee: **FOXCONN INTERCONNECT TECHNOLOGY LIMITED**, Grand Cayman (KY)

(**) Term: **15 Years**

(21) Appl. No.: **29/589,998**

(22) Filed: **Jan. 6, 2017**

(30) **Foreign Application Priority Data**

Jul. 8, 2016 (CN) 2016 3 0309716

(51) **LOC (10) Cl.** **14-02**

(52) **U.S. Cl.**

USPC **D14/433**

(58) **Field of Classification Search**

USPC D14/356, 432-434, 453, 454, 511, 203.8, D14/209.1, 238.1, 240, 125; 439/638, 439/928, 105, 502; 710/303, 304; 361/679.41, 679.55, 679.56; D13/110, D13/133, 146

CPC H01R 24/64; H01R 24/62; H01R 12/714; H01R 13/506; H01R 13/6658

See application file for complete search history.

(57) **CLAIM**

The ornamental design is for a adapter, as shown and described.

DESCRIPTION

FIG. 1 is a perspective view of a adapter showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.
